UNITED STATES PATENT OFFICE

154,582

DESIGN FOR A DOLL

Genevieve E. Bailey, Butte, Mont.

Application November 17, 1947, Serial No. 142,578

Term of patent 7 years

(Cl. D34—4)

To all whom it may concern:

Be it known that I, Genevieve E. Bailey, a citizen of the United States, residing at Butte, in the county of Silver Bow and State of Montana, have invented a new, original, and ornamental Design for a Doll, of which the following is a specification, reference being had to the accompanying drawing, forming part thereof.

I claim:

The ornamental design for a doll as shown.

GENEVIEVE E. BAILEY.
